UNDERWATER DIVING LIGHT

Owsley H. Brigham, 7510 Morningside Drive,
Indianapolis, Ind. 46240

Filed Jan. 20, 1967; Ser. No. 5,490

Term of patent 14 years

(Cl. D48—24)

Fig. 1.

Fig. 2.

Fig. 3.

Fig. 5.

Fig. 4.

FIG. 1 is a side elevation of an underwater diving light embodying my invention.

FIG. 2 is a front elevation of the underwater diving light of FIG. 1.

FIG. 3 is a top plan view of the diving light of FIG. 1.

FIG. 4 is a bottom plan view of the diving light of FIG. 1.

FIG. 5 is a rear elevation of the diving light of FIG. 1.

The characteristic features of my design reside in the specific configuration and location of the handle as shown.

I claim:

The ornamental design for underwater diving light, as shown and described.
